JOSEPH W. LEGG, OF WILKINSBURG, PENNSYLVANIA, ASSIGNOR TO WESTINGHOUSE ELECTRIC & MANUFACTURING COMPANY, A CORPORATION OF PENNSYLVANIA.

OSCILLOGRAPH GALVANOMETER.

Application filed January 12, 1923. Serial No. 612,335.

My invention relates to galvanometers and particularly to galvanometers adapted for service in oscillographs.

One object of my invention is to provide a device of the above indicated character that shall be extremely compact in construction and effective in operation.

Another object of my invention is to provide a galvanometer subject to relatively high voltages that shall be adequately protected and that may be easily and safely manipulated.

Figure 1 of the accompanying drawing is a plan view of a galvanometer embodying my invention.

Figure 2 is a view taken partially in end elevation and partially along the line II—II of Fig. 1.

Fig. 3 is a front view, partially in section and partially in elevation, of a portion of the device shown in Fig. 1.

Fig. 4 is an enlarged cross-sectional view of a well structure, constituting part of my invention, taken at right angles to the structure shown in Fig. 3.

Fig. 5 is a detail view taken at right angles to Fig. 4 and

Fig. 6 is a detail view of one member of the device.

A main insulating supporting structure comprises a horizontal base plate or member 1, vertical plates 2 disposed adjacent to the ends thereof, an intermediate vertical plate 3 extending between the inner edges of the end plates 2 and relatively short vertical partition plates or members 4 extending from the intermediate plate 3 to one side edge of the base plate. The construction described above divides the supporting structure into a relatively large compartment in which a coil 5 is disposed and three smaller compartments in which well structures 6 are disposed.

A cylindrical magnetizable core member 7 extends through the coil 5 and through the end plates 2 and is provided at its ends with horizontal yoke members 8 that extend forwardly to positions opposite a center line through the well structure 6. Nuts 9 secure the yoke members 8 to the core member 7 and longitudinal rods or bars 10 serve to hold the vertical plates together.

Each of the plates 4, as shown more clearly in Figs. 3 and 5, is preferably built up of a plurality of relatively thin layers of paper, or other suitable material, having central recesses for the reception of a pair of magnetizable disks or pole members 12 and central layers 14 which extend between, and beyond the edges of the members 12.

The latter are provided with flanges 15 serving to enlarge the adjacent faces thereof and to better anchor the members in the paper layers, constituting the partition, which are impregnated with a binder and hardened under heat and pressure. This construction provides a single series magnetic path for all of the well structures 6 comprising the core member 7, the yoke members 8 and the pole members 12. The thin partitions 14 permit the passage of magnetic flux but, with the other insulating parts, prevent short circuiting between independent circuits of the several well structures which are hereinafter set forth. The yoke members 8 are provided with openings for the reception of screws 17 that extend therethrough. The pole members 12 are provided with trunnion portions 19.

Each well structure 6 comprises a cylindrical cup member 20, preferably of non-magnetic, non-corrosive material, such as molded insulating composition, having a top opening 21, side openings 23, a front opening 24 and a bottom opening 25, the latter of which constitutes a drain outlet normally closed by a screw or plug 26.

The side openings 23 are adapted for the reception of transverse oppositely aligned pole members 28 having reduced inner end portions 29 and laterally expanded or discoidal outer end portions 30 for co-operative engagement with the outer surfaces of the pole members 12 in the plates 4. The outer surfaces of the outer end portions 30 are provided with grooves 32 and 33, as shown in Fig. 2, whereby the well structures may be inserted into operative position between the plates 4. In effecting such insertion, the well structures are lowered while in slightly laterally offset position relative to the final positions thereof to pass the grooved portions 32 over the trunnions 19, after which the grooved portions 33 are moved horizontally to place the trunnions 19 in the rear end of the grooves 33.

Reflection preventing members 35, secured in position by screws 36, are provided with side arms 37 which fit the horizontal grooves 33 to hold the well structures in position on the trunnions 19.

Plate or cover members 39, secured in fluid-tight position over the top openings 21 in the cup members 20, by screws 40, are provided with openings 42 therein and forwardly projecting portions 43 having upper bearing surfaces 44 and front edge flanges 45. Metal structures 47 adapted for the support of vibrating elements 48 are mounted in fluid-tight relation on the cover members 39, in engagement with the bearing surfaces 44 and are provided with depending portions 50 upon which the elements 48 are mounted. The structures 47 are yieldably held in position against the surfaces 44 by screws 51, that extend through bosses 52, and resilient washers 53 disposed between the heads of the screws 51 and the outer ends of the bosses 52.

Segmental gear members 55, secured to the structures 47, co-operate with pinions 56 for adjusting the vibrating elements 48 angularly about the longitudinal axis of the cup members 20. The pinions 56 are mounted in the cover members 39 through shafts 59 that are provided with insulating handles 60.

Guide or supporting members 62, preferably of ivory are provided for the elements 48, and are secured to the depending portions 50 by screws 63.

Each vibratory element 48, preferably of flat strap construction, extends from a member 65, grounded to the portion 50, over the ivory guides 62, a pulley or roller 66 and from the pulley 66 back over the guides 62 to a conductor 68. The latter extends through an insulating bushing 69 in the portion 50 to a terminal device 70 which constitutes one terminal of the element 48 and is insulated from the metal structure 47 by a bushing 71. A similar terminal device 72, constituting the other terminal of the element 48 is grounded to the metal structure 47 by a screw 73. The above construction provides two strands of the element 48 between the guides 62 disposed in parallel side-by-side relation slightly spaced apart. A mirror 75 is mounted on the element opposite the front opening 24 in the cup member 20. The opening 24 is sealed by a glass plate 76 which is inclined slightly to prevent reflections from a beam of light that is adapted to enter an opening 77 in the member 35 being projected normal to the surface of the mirror 75. The member 35 is also cupped or depressed to similarly prevent reflections being projected normal to the surface of the mirror 75.

The pulley 66 is mounted at one end of a member 80 that is centrally pivoted, by a pin

81, between depending portions 82 of the portion 50. A vertically disposed helical spring 83 is secured, at its lower end, to the other end of the member 80, by a pin 84, and, at its upper end, to an adjustable screw 86 70 that is mounted in an enlarged portion 87 of the member 65 and is provided with a nut 88.

In mounting the element 48, the member 80 is initially moved slightly clockwise 75 from the position shown in Fig. 4 against the action of the spring 83 and wedged in such position, as by placing a splint between the member 80 and the portion 82. This operation raises the pulley 66 slightly. 80 The element 48 is then secured to one of the members 65 or 68, as by soldering, and brought down over the guides 62 and around the pulley 66. The element is then drawn upwardly, under slight tension over the 85 guides 62 and similarly secured to the other member 65 or 68. When the wedge is withdrawn to release the member 80, the latter will be moved counter-clockwise by spring 83 to place the element 48 under the desired 90 tension.

The pin 81 being at the center of the member 80 there will be no tendency for the latter to be displaced relative to the portion 50 when the latter is jarred. Thus when the 95 device is subjected to vibration or jarring, the element 48 will be under no fracturing stresses other than those caused by its own inertia and, since the element is extremely light in weight as compared to its tensile 100 strength, it is practically proof against damage from such causes.

As shown more clearly in Fig. 1, the reduced inner ends of the pole members 28 are sloped from rear to front to provide adjacent concentrated poles between which the vibratory element 48 extends. The space, at the rear of the pole members 28 thus provided is occupied by the portion 50 and the spring 83. 110

In mounting the structure 47, the portion 50 with the element 48 and the accompanying parts is lowered through the opening 42 along a vertical line that is displaced to the right of these parts as viewed in Fig. 4. This permits such parts to be lowered to the proper levels while clear of the pole members. After this movement, the structure 47 is moved forwardly or to the left as viewed in Fig. 4, until the forward edge thereof engages the flanges 45 on the projection 43. This action brings the screw 51 into register with an opening therefor in the member 39, after which the pinion 56 and its handle 60 are placed in position. 115

An adjusting rod or bar 90, see Figs. 1 and 2, is provided at its upper and lower ends, with right-hand and left-hand screw-threaded portions 91 and 92, respectively, and also has a handle portion 94. The por-

tion 91 is operatively mounted in a block 95 that is horizontally pivoted by trunnions 96, between two bearing blocks 97 secured to the plate 3. The portion 92 is operatively mounted in a block 98, as shown in connection with the central galvanometer element in Fig. 1, that is horizontally pivoted by trunnions 99, between two bearing blocks 100 secured to the cup member 20.

10 In operation, the device is adapted to be placed in an oscillograph box or container, and the coil 5 is connected to a small direct-current source (not shown) to energize the core member 7, the yoke members 8 and the 15 pole members 12 and 28. The members 7, 8, 30 and 12 constitute a single series magnetic circuit having air gaps between the reduced ends of the pole members 30 in which are disposed the vibratory elements 20 48. The latter are adapted to be connected to a circuit to be tested through the binding posts 70 and 72 and, when energized, react with the magnetic field between the pole members 30 to cause the mirrors 75 to 25 vibrate, the instantaneous deflection of the mirror being proportional to the instantaneous value of the current being studied. Light beams are directed through prisms, according to the usual practice through the 30 openings 77, to the vibratory mirrors 75 and, from the latter, back through the openings 77 to a photographic film or other device for observation of the circuit under test.

35 Since it is desirable to direct concentrated beams or pencils of light and to avoid incidental reflection, the glass plate 76 is inclined and the member 35 is cupped or curved inwardly at its outer surface to render the surfaces of the mirrors 75 the only surfaces normal to said beams. To further insure the absence of reflection, the surfaces of all parts other than the surfaces of the mirror are rendered as nearly reflection 40 proof as practicable.

The elevation of the reflected light beams from the mirror 75 to the photographic films may be adjusted by manipulation of the handles 94. Turning of these handles by 45 reason of the right-hand and left-hand screw-threaded portions 91 and 92, respectively, on the rod 90, tilts the cup members 20 to any desired angle.

The light beams may be adjusted laterally by turning the handles 60, which movement turns the pinions 56 and, consequently, the gear segments 55 and the vibrating elements 48.

Damping of the elements 48 is effected by 50 bodies of suitable fluid (not shown) which the cup members 20 are adapted to receive through the top openings 21 thereof. The bottom openings 25 permit draining of the cup-members 20. Since the metal structures 55 47 are mounted in fluid-tight relation to the

cover members 39, the device may be transported without removing the damping fluid from the cup members 20.

By the use of the series-related pairs of pole members in the magnetic circuit, a 70 single energizing coil may be employed, instead of a separate coil for each flux gap, and economy of space obtained to a high degree. This feature is especially useful in obtaining a readily portable device, such 75 as an oscillograph, where the previous devices have been many times larger and heavier and have not been portable in the sense that a single person could carry them.

Further, the particular method of mounting the vibratory elements whereby the elements are not readily broken is particularly desirable because such elements have heretofore been a great source of annoyance 80 from this cause.

While I have shown and described a particular form of my invention, changes may be effected therein without departing from the spirit and scope thereof, as set forth in 85 the appended claims.

90 I claim as my invention:

1. An instrument comprising a magnetizable core member, a pair of pole members, disposed in series magnetic flux path relation thereto, means disposed in a gap between said pole members for co-operation with the magnetic field therebetween and a body of laminated insulating material constituting a partition between one of said pole members and said core member. 100

2. An instrument comprising a magnetizable core member, a pair of pole members, disposed in series magnetic flux path relation thereto, means disposed in a gap between said pole members for co-operation 105 with the magnetic field therebetween and a body of laminated insulating material constituting a partition between one of said pole members and said core member, said body having an intermediate imperforate sheet or sheets extending laterally over and beyond the end of the pole member and a perforate sheet or sheets secured to said imperforate sheet or sheets to thicken the partition outside the metallic flux path. 110

3. In an instrument, the combination with a flux responsive element, of a magnetic flux path structure having a flux gap in which said element is disposed and including two magnetizable members having adjacent perimetrically flanged end portions and a body of insulating material having a portion constituting a partition between said end portions and a portion surrounding said partition and said flanges to assist in holding said members together. 115

4. A galvanometer comprising a plurality of pairs of series-related magnetic pole members, a vibratory element in a gap between each pair, a pair of spaced magnetizable

members between each pair of pole members, and an insulating structure surrounding, and disposed between said spaced magnetizable members, said insulating structure being 5 constructed of a plurality of superposed layers of insulating material bound together to constitute a single rigid structure.

5. A galvanometer comprising a well structure, magnetic pole members projecting 10 inwardly from opposite sides, thereof, a vibrating element for vertical disposition in the well between the pole members, a removable supporting structure for the element, said structures being constructed and 15 related to permit the element to be freely placed in the well and withdrawn therefrom in the direction of the longitudinal axis of the well along a path laterally removed from said pole members and to be moved 20 transversely to and from position between the pole members, means for limiting said transverse movement to position the element in predetermined relation to the pole members, and means for accurately guiding the 25 element into position in said well.

6. A galvanometer comprising a well structure having an opening in a side wall thereof, a vibratory element vertically disposed in the well, a mirror carried by the element opposite and facing said opening, and 30 a reflection shield for said opening having a curved-wall portion of substantial cup-shape bowed toward said mirror and a central opening opposite the mirror.

35 7. A galvanometer comprising a supporting structure, a well structure having a light-transmitting opening therethrough and pivotally mounted on said supporting structure, and a member for holding said

well structure in operative position on said supporting structure and having a reflection-shield portion adjacent to said opening.

8. A galvanometer comprising a well structure having a top bearing surface, a vibratory element, a supporting member for 45 the element having a portion projecting into the well and a transverse portion engaging said bearing surface for angular slidable movement thereon and means for vertically yieldably securing said transverse portion 50 in position on said surface.

9. In a galvanometer, the combination with a pair of spaced parallel partition members and a substantially vertical well member disposed therebetween, of a bearing structure between each partition and the adjacent side of the well member comprising a trunnion extending transversely to the longitudinal axis of the well, and a trunnion bearing member having a transverse 60 groove, said bearing structure permitting the well member to be moved to and from pivoted position between said partition members.

10. A galvanometer comprising a fluid-tight well structure for the reception of a liquid medium, a plate-like member movably mounted in fluid-tight relation to the top of and substantially overlying said well structure, a member projecting from said plate-like member into said well structure, and a vibratory element mounted on said projecting member.

In testimony whereof, I have hereunto subscribed my name this 18th day of December 1922.

JOSEPH W. LEGG.
